UNITED STATES PATENT OFFICE.

ALFRED L. DAY, OF NEW YORK, N. Y.

CRYPTOGRAPHIC PERFORATOR.

SPECIFICATION forming part of Letters Patent No. 739,399, dated September 22, 1903.

Application filed May 5, 1903. Serial No. 155,731. (No model.)

To all whom it may concern:

Be it known that I, ALFRED L. DAY, a citizen of the United States, residing in Manhattan borough, New York city, in the county of New York and State of New York, have invented certain new and useful Improvements in Cryptographic Perforators, of which the following is a specification.

This invention relates, primarily, to means for enabling either numbers or letters, or both, to be punched or otherwise marked upon bank-checks, labels, and other papers by the use of a far smaller number of punches or markers than has heretofore been the practice. In my application filed March 19, 1903, Serial No. 148,518, is disclosed a code of marking or a system of cryptography, whereby a number or other character may be represented by two or three marks by using only two or three punches in place of twenty or more punches or markers heretofore used. One of the leading features of said method of cryptographic notation consists in making a universal base-mark for all numbers and in placing indicative marks at different distances from said base-mark to represent different digits or numerals, whereby the first indicative mark, read in connection with the base-mark, signifies the digit "1." The second indicative mark in connection with the base-mark signifies "2," the next "3," and so on. By charting the indicative marks in three equidistant rows and having three marks in each row nine digits may be represented, and any of them may be easily read, as the reader has merely to gage by the eye the distance and direction of any indicative mark from the base-mark. The base-mark not only serves for aiding the reader to determine which of the nine positions the indicative mark occupies, but also enables him to tell which way to hold the paper in order to read the cryptogram right. As set forth in said application, by proper combinations a cryptographic system based upon said nine indicative holes, in connection with two additional indicative holes, may be used for indicating any number from "1" to "99," and by employing a series of indicative groups in connection with two different universal base-marks any desired date may be indicated, the first section of the cryptogram in-

dicating the ordinal of the month, the second section the day of the month, the third section the digits of the year, and all by the use of a far smaller number of punches or marks than has been found practicable heretofore. In said application is illustrated a perforating-machine having four groups of punches and four corresponding punch-controlling wheels in connection with two different base-punches, each wheel being adjustable by itself, so that it may be set to different positions for operating different punches in the four groups, the first wheel being used for the months, the second and the third for the days of the month, and the fourth for the year.

The leading objects of the present invention are to simplify the mechanism and to condense the cryptograms formed thereby. The improvement is illustrated herein as applied specifically to the means for denoting the days of the month. In said application the days are indicated by means of two groups of punches controlled by two pattern-wheels set side by side and adapted to form two cryptogram-sections, each of which must be independently deciphered in order to determine by their combination the day of the month denoted thereby. In the present instance I contrive to denote the day of the month by a single cryptogram or cryptogram-section, thus facilitating the deciphering thereof. The perforated tens-wheel and the perforated units-wheel I mount telescopically one within the other, provision being made for combining the groups of holes or patterns upon one wheel with those upon the other wheel; and by means of these wheels I control a single group of punches. Such punches as are not operable by the selected pattern portion of the outer wheel pass through the holes therein and are presented to the inner wheel, and are operated thereby according to the pattern thereon, which registers at the time with the working pattern on the outer wheel, some of the punches being received by the idle holes in the inner wheel and one or more of them being operated by the unperforated portion of the latter. By using one wheel for tens and the other for units and forming, say, fifteen patterns on each wheel any number from "1" to "99" may be indicated cryptographically by setting the wheels to different combina-

tions, by the use of, say, eleven punches or other markers, the reduction in the number of punches, as well as the compactness of the cryptogram punched thereby being important.

In the drawings forming part of this specification, Figure 1 is a vertical longitudinal section of a perforating-machine equipped with means for perforating cryptograms. 10 This view corresponds except in a few particulars to Fig. 3 of Patent No. 475,440, issued May 24, 1892. Fig. 2 is a plan of the machine shown in Fig. 1 and corresponds except in some particulars with Fig. 6 in said 15 patent. Fig. 3 is a diagram of the development of the peripheries of the four punch-controlling pattern-wheels shown in Fig. 2 and used in marking dates. Fig. 4 shows a series of groups of cryptograms made by the 20 use of my present invention and indicating the different dates specified under the cryptograms. Fig. 5 is a sectional front view corresponding generally to Fig. 2 in said patent, but showing in elevation the series of three 25 groups of cryptographic punches and four wheels controlling them, two of the wheels controlling the central group. Fig. 6 is a chart of a cryptographic system for use in marking any number from "0" to "99," inclusive. Fig. 7 is an enlarged fragment of 30 the telescoping pattern-wheels, the outer being broken away to show the registering idle holes in the inner wheel. Figs. 8 and 9 are perspective views of the outer and inner telescopic pattern-wheels. Fig. 10 is a diagram 35 of pattern-wheels for punching from "1" to "99." Fig. 11 is a date-chart. It may also be regarded as a plan of the punches which are used in the perforating-machine shown 40 in other views.

In the several views like signs denote like parts.

The framing of the machine comprises a base-plate 20, upon which is fastened a block 21, integral with which is formed a hollow needle case or holder 22, within which are mounted in this instance three ranges of groups of vertical needles or punches 23, 24, and 25, respectively. Said punches at their 45 upper ends are guided in a fixed perforated plate 26 and at their lower ends in a soft metal filling 27, supported upon a fixed plate 28. The punches are adapted to move downwardly, and beneath them is provided a platen 50 or female-die plate 29, having perforations 30, corresponding with the punches, said platen forming a table upon which the checks or other papers may rest while being perforated, an opening 31 between the punch-holder and 55 platen being left for the insertion of papers. The punches are provided with shoulders 32, which are engaged by a lifting-plate 33, the latter being raised by members 34 to return the punches to their normal position after actuation in the manner set forth in said patent.

Above the punches four annular punch-controlling wheels 35, 36, 37, and 38 are rev-

olubly mounted upon a fixed arbor 39, so that any wheel may be turned to any desired position. The periphery of each of the wheels 70 35, 37, and 38 is preferably divided into twelve facets 40, and on these are formed groups or patterns of idle holes 41, into which enter during the descent of the group of wheels—i. e., during the punching movement—such 75 punches in the middle range 24 as are not intended to be operated, it being understood that the unpierced portion or portions of each of said facets 40 operate to drive down one or more of the punches in a manner set forth in 80 said patent.

The wheel 37 consists, preferably, of a thin annular shell 42 and an interior integral flange 43 at one side of the shell, the shell and flange being preferably equal in thickness to one of the plain wheels 35 and 38, while the wheel 36 has a cylindrical contour to fit snugly within the shell 42, so as to support the same, while being capable of turning freely therein. The wheel 36 turns directly on the arbor 39 and has a peripheral integral flange 44, provided with facets 40 to match the facets on the other three wheels.

For effecting the downward movement of the wheels the arbor 39 is fixed upon a lever 95 45, pivoted at 46 upon the framework and operated by a link 47 and toggle-lever 48, a return-spring 49 for the wheel-lever 45 being also provided. It may here be noted that plates 50 51, provided upon the lever 45 and 100 flanking the bottom portions of the wheels, serve to operate the outside ranges 23 and 25 of needles for perforating the word "Paid" or any other words or marks in the manner set forth in said patent. Each wheel is 105 provided with a locking or retaining pin 52, which may enter any of the radial holes 53, formed in the wheel between the facets 40, and may also enter a locking-groove 54, formed in the fixed arbor 39 in the manner 110 set forth in said patent.

In Fig. 6 is shown a chart of a simple grouping of punches arranged in three rows, three in a row, and numbered from "1" to "9," inclusive. At the left-hand upper corner of the 115 diagram is a two-part base-punch 54—that is to say, a punch adapted to make twin holes in the paper, these twin holes serving as position-holes, from whence the distance and direction of any one or more of the other holes 120 may be gaged by the eye of the reader; and since they always occur at the left-hand upper corner of my cryptogram in which they are used the reader is enabled to tell in what way to hold the paper in order to read the 125 cryptogram correctly. Any other style of base-punch, whether multipartite or simple, may be employed. It will be understood if the punch "1" is used alone of the nine indicative punches the reader will perceive that 130 the hole made thereby occupies the position of the first hole in the first row, and hence that it is intended to represent "1." Likewise, if the second punch in the first row is

used alone the reader is enabled to tell, from judging the distance between its hole and the base-hole, that the second punch in the first row was used, from which he understands 5 that the hole reads "2," and so on with the remaining holes in the series of nine, the reader being easily able to tell in which row the hole falls and at which point in the row, whether the middle point or at one of the end points. 10 At a point without said three rows and preferably thereabove I provide, as at Fig. 6, a punch marked "0," which makes a hole to represent a cipher, so that if said hole is punched in connection with any of the other 15 nine digit-holes the combination represents "10," "20," "30," or other multiple of ten, as the case may be, up to ninety. Said punch "0," it will be noted, has a staggering relation to the punches "1" and "2." In the 20 same row with the punch "0" I provide another punch marked "D," which has a staggering relation to the punches "2" and "3," and indicates a doublet, so that if said punch "D" is used in connection with any of the 25 digit-holes from "1" to "9," inclusive, it represents "11," "22," "33," or any multiple of eleven up to ninety-nine.

In denoting numbers above "11" two punches may be used, such as "1" and "2" 30 to indicate "12," "5" and "6" to indicate "56," and so on. If, however, it is desired to denote a number in which the tens digit is greater than the unit digit I prefer to employ three punches in place of two, the third 35 punch being the "0," seen at the top of the chart, which it will be understood is always to be read in connection with the greater of the two digits punched, so that in case, for instance, a cryptogram is punched with the 40 "3," the "6," and the "0," the "6" and the "0," taken together, signify "60," and these, together with the "3," signify "60" plus three, or "63," and not "36," since if "36" were intended the "0" would not be used. In 45 the last diagram at Fig. 4 this cryptogram is illustrated at the right-hand side. The holes "0" and "D" are arranged in staggering relation to the other holes in the chart, so that neither of the former can ever be 50 punched in vertical line with any digit-hole which is punched in connection therewith, whereby liability of confusion and mistakes are avoided. In reading a cryptogram one hole directly above another indicates a combination of two of the digits "1" to "9," inclusive, while two holes, one above the other, but slightly out of line therewith, indicates a combination of a digit with either a "double" 55 or a "0," as the case may be. The staggering of "0" and "D" thus affords a material aid in the quick deciphering of the cryptograms.

It will be understood that in Fig. 6 is shown only one illustration of a method of 60 cryptographic notation and that other methods or other groupings may be used within the scope of my improvements and not only

for purposes of notation, but also to indicate letters or other characters, if desired. I divide the periphery of each of the punch-controlling wheels 35, 36, and 38 into as many facets as are desired, and it will be understood that every idle hole is seen in the pattern upon each facet at Fig. 3, except that hole which would correspond to the particular punch or punches which that pattern or facet is intended to operate. The flange 44 of wheel 37 is also divided into facets, and the wheel itself is provided with idle holes forming the desired patterns. At said figure 80 is illustrated a development of the patterns of the four wheels 35 to 38, inclusive. At the beginning of the first wheel 35, which is shown at the right hand of the set of wheels, it will be seen that idle holes are provided 85 for all the punches excepting the first punch in the first row, it being understood that the patterns are all negatives. This pattern will control the punch for marking "1," and is hence indicated as 1 in said figure. The next 90 facet on the wheel shows idle holes for all of the punches except the second one in the first row, which punch makes a hole or mark in the cryptogram to indicate "2," and hence said facet is indicated as 2 in the margin. 95 The third facet is adapted to operate the third punch in the first row, and so on down to the ninth facet, which operates the third punch in the third row. In the tenth facet idle holes are shown for all the punches except "1" and "0," which, taken together, make "10," so that in the margin said facet is marked 10. The next facet shows idle holes for all of said punches except the "1" and the "D," (standing for "double.") Therefore the holes punched by this facet would mean "11," so that it is marked 11 in the margin. The next facet shows idle holes for all the punches except "1" and "2," which indicate "12," as marked in the margin. 110

It should be explained that, in connection with the retaining-pins 52, which are inserted in the pin-holes 53 between the wheel-facets, I employ a series of whole numbers, from "1" to "12," which I stamp upon the wheel between the facets 40 in proximity to said pin-holes 53, so that when a pin passes through any of said holes and into the registering slot 54 in the fixed arbor 39 the wheel is in position for controlling a punch or punches to 115 make a cryptogram for the particular number stamped opposite said pin-hole. For instance, when said pin is in the hole marked 3 on the wheel 35, Fig. 3, this being at the top of the wheel, the facet marked 3 in the margin is at the bottom of the wheel and in position for coöoperating with the punches therebelow. Thus by inserting the pin 52 in any selected hole and positioning the wheel thereby the operator may set the machine 120 for making any desired cryptogram. It will be understood that it is not essential in all cases that the particular controlling means herein shown be employed nor that the

punches or needles in all cases be mounted independently of the wheels, it being understood that my improvements may be applied to any construction of perforator or marker 5 and that any kind of punching or marking means may be mounted and operated in any desired manner. In this instance, the first wheel 38 is used for indicating the ordinal of the months. The first pattern on the second 10 wheel 37 is provided with idle holes for all the punches, and is therefore denominated "Blank" in the margin, the wheel when not in use being turned until this pattern is over the punches. The second pattern is intended 15 for indicating the tens digit "1" in punching numbers from "11" to "19," inclusive. The third pattern controls the next punch for indicating the twenties digit "2" in making numbers from "23" to "29," inclusive. The 20 remaining patterns are used for punching "20," "21," "30," and "31," respectively. At suitable points the terms "Blank," "1," "2," "20," "21," "30," and "31" are marked on the wheel opposite the appropriate pin-holes 53, so 25 as to guide the operator in setting the wheel.

TriPLICATE base-punches 55, (shown at Figs. 4 and 5,) which are preferably of larger diameter than the indicative punches, it will be understood, are mounted between the 30 group of punches 56 and the first-described group of punches, (indicated as 57 at Fig. 5.) It will also be understood that no idle holes are provided for said base-punches in any of the wheels, but that the unperforated edge 35 portions of the facets of the wheels bear directly down upon the base-punches, so that the latter are forced through the paper at every operation of the machine, so as to punch universal or uniform base-holes for all cryptograms, thereby aiding the reader in deciphering the number or sign denoted by any 40 cryptogram.

The third wheel 36, which is within the second wheel 37, controls the same group of 45 punches 56 as are controlled by the wheel 37. The wheel 36 is used for the unit digits in indicating the days of the month and is provided with patterns for "Blank" and also for "1" to "10," inclusive, and also for "Double." The wheel is turned to "Blank," and also when either "20," "21," "30," or "31" is to be punched by the outer wheel 37, and it is turned to "Double" when the outer 50 wheel is turned to either "1" or "2" for punching either "11" or "22." The fourth punch-controlling wheel 35 may be similar to the first wheel 38 in all respects, the group of punches controlled thereby being indicated at 60, Fig. 5, so that said wheel is enabled to 55 indicate from "1" to "12," inclusive, thereby denoting any selected year in a cycle of twelve years. Between the groups 60 and 61 is provided a two-part base-punch 62. It will be understood that any suitable base-punch 60 65 may be employed in carrying out my invention. Wheels having a greater or smaller number of patterns may be employed, and

there may be less or more than four wheels mounted in a machine for meeting various requirements. The mechanism operates generally in the manner set forth in said patent. The operator by manipulating the pin 52 for each of the number-wheels is enabled to set the same, being guided by the normal numbers printed opposite the pin-holes 53. Then 70 the paper is inserted in the opening 31, and the handle 48 is brought down to operate the punches and form a cryptogram. At the same time the groups of punches 23 and 25 are operated for punching any desired normal words or characters in connection with 75 the cryptogram, although it will be understood that said groups are put in principally for the sake of illustration and that my invention may be employed either with or without extraneous punching or marking means, as may be desired. If the operator desires 80 to punch "March 24, 1903," for instance, he sets the first wheel with the pin 47 in the hole 53 opposite the numeral "3" stamped on said 85 wheel, the pattern 3 being now at the bottom of the wheel. He then similarly adjusts the second or outer telescopic wheel 37 to the pin-hole "2," the third wheel 36 to the hole "6," and the fourth wheel 35 to the hole "3," thereupon inserting the paper and bringing down 90 the handle 48. By this means there will be punched in the paper a cryptogram, such as seen in the upper diagram at Fig. 4, from which the reader will readily see that one indicative 95 hole stands at the third point in the upper row at the left of the first base-hole 57, thereby indicating the numeral "3," which is the ordinal for the month March; that a hole is punched at the second point in the first row 100 at the right of said base-hole, thereby indicating a "2;" that a hole is also punched in the first point in the second row at the right of said base-hole, thereby indicating a "4," which, taken together with said "2," reads 105 "24," meaning the 24th of March. It will also be observed that at the right of the second base-hole 62 a hole is punched at the 110 third point in the first row, meaning "3," whereby it will be understood that the cryptogram means March 26, 1903. In the following cryptogram at Fig. 4 a hole "3" and a "0" hole are made by the second wheel, indicating "30," the third wheel being set to "Blank" and the whole cryptogram indicating 115 June 30, 1906, as is apparent. In the third cryptogram in said figure the "31" is made by the second wheel, and there is shown at the right of the second base-hole a hole for "1" and a hole for "double," indicating 120 "11," the whole cryptogram reading "January 31, 1911." In the fourth cryptogram the second wheel is set with the pin 51 at the point marked "Blank," while the third wheel 36 is set to punch a hole "3," the whole cryptogram indicating December 3, 1945. It will be understood, of course, that for making "45" 125 a differently-perforated year-wheel may be substituted for that illustrated at 35, Fig. 3.

At the last cryptogram, Fig. 7, the year indicated is "63," the hole "6" and the hole "0" being taken together to mean "60," and the two holes, taken together with the "3," indicating "63," it being understood that if "36" were intended the "0" hole would be omitted. With a little practice it becomes possible to read at sight any simple cryptogram formed by my method.

- 10 While I prefer to use a base or position punch in nearly all cases, it will be understood that certain features of my improvements may be employed without said base-punches. It will be understood that different users of my invention may have different cryptogram-charts, with or without the described specific grouping of the punches or other markers.

There are many purposes for which it is impracticable to use a large number of punches in perforating paper, for which purposes my invention has great utility, particularly since by the use of only eleven punches in the group 56 any number may be punched from 25 "0" to "99." It is also useful in cases where it is desired to place secret marks upon paper or other articles to indicate dates or figures or other characters. For instance, the date of manufacture of an article may be 30 marked thereon, so that in case said article is returned to the manufacturer he may ascertain the date at which he sent it out, while the mark is illegible to the general public. It will be seen that a date or other number 35 can be punched or marked in much less space than has been required heretofore. According to patent, for instance, it requires six wheels to make a date which can be made according to my invention with four wheels, 40 using only three groups of punches and occupying less space upon the bank-check or other paper, and it will also be understood that by using fewer needles it becomes possible to perforate a thicker pack of papers by 45 a single operation, which is a desideratum.

It will be seen that I provide a series of cryptographic markers and make universal base-marks and different individual indicative marks whereby to form a series of cryptograms, the indicative marks of the different members of said series of marker being respectively located at different points with relation to the base-marker, so that by noting the position of the various indicative marks 55 produced thereby relatively to the universal base-mark the reader is informed of the characters represented by the different cryptograms. It will also be seen that the indicative marks of the series of markers are not 60 only located, respectively, at different points with relation to the base-mark, but are also so interrelated that if collated they would fall at substantially equidistant points in substantially equidistant rows—as, for instance, 65 charted in Fig. 6.

While I have herein illustrated a machine adapted to perforate cryptograms upon

checks and the like, it is to be understood that the invention may be carried out in numerous ways, and that a series of suitable 70 markers may be employed for marking otherwise than by perforating, and that the invention broadly includes such a series, whether with or without mechanism for operating the same.

75 Variations may be made in applying my invention to cryptographic and other marking or punching machines and portions of my improvements may be used without others.

Having thus described my invention, I 80 claim—

1. In a marking-machine, the combination with a group of markers of two pattern-wheels mounted one within the other; said wheels having registrable idle holes for the markers; 85 said idle holes being mounted upon each wheel in a series of groups, and different holes being omitted from the different groups, whereby the markers may be operable by the unperforated portions of the outer wheel and 90 may upon passing through the holes in the outer wheel be operated by the unperforated portions of the inner wheel, and may also be received by the registering idle holes in both wheels.

95 2. In a marking-machine, the combination with a group of markers of two independently-adjustable pattern members mounted one behind the other and co-operatively controlling all of said markers.

100 3. In a marking-machine, the combination with a group of markers of two independently-adjustable pattern-wheels mounted one within the other and co-operatively controlling all of said markers.

105 4. In a marking-machine, the combination with a group of markers of two independently-adjustable pattern members each having perforations and mounted one behind the other; said perforations in each of said members being arranged in a series of groups to form different patterns and means for enabling any group upon either member to co-operate with any group upon the other member to control said markers.

110 5. In a marking-machine, the combination with a group of markers of two independently-adjustable pattern-wheels each having perforations and mounted one within the other; said perforations in each of said members being arranged in a series of groups, and means for holding any group upon either wheel in register with any group upon the other wheel, whereby one or more of markers in the group may be controlled by the unperforated portion thereof.

115 6. In a marking-machine, the combination with a group of markers, of independently-adjustable combinable pattern devices each having means for controlling said markers.

120 7. In a marking-machine, the combination with a group of markers, of two independently-adjustable wheels each having patterns formed by perforations therein, and the pat-

terns of one wheel being combinable with the patterns of the other wheel for controlling all of said markers.

8. In a marking-machine, the combination 5 with a group of markers, of a support, and telescopically - connected pattern - wheels mounted upon said support; each wheel being perforated to form a set of patterns, and the patterns upon one wheel being combinable with the patterns upon the other wheel.

9. In a marking-machine, the combination with a group of markers, of a support, a wheel mounted thereon and having a peripheral 15 flange, holes in said wheel forming a group of patterns for controlling said markers, a wheel mounted telescopically upon said flanged wheel and also having patterns each formed of groups of holes, the patterns in one wheel 20 being combinable with those in the other.

10. In a marking-machine, the combination with a group of markers, of a support, a wheel mounted thereon and having a peripheral flange, holes in said wheel forming a group of 25 patterns for controlling said punches, a wheel mounted telescopically upon said flanged wheel and also having patterns each formed of groups of holes, the patterns in one wheel being combinable with those of the other, said 30 outer wheel having an interior flange, and each of said flanges being perforated, and means including members adapted to be received by said flange perforations, for setting said wheels so that their patterns may coöperatively control the markers.

11. In a perforating-machine, the combination with a group of punches of two pattern-wheels mounted one within the other; said wheels having registrable idle holes for the 40 punches, said idle holes being mounted upon each wheel in a series of groups, and different holes being omitted from the different groups, whereby the punches may be operable by the unperforated portions of the outer wheel, and 45 may upon passing through the holes in the outer wheel be operated by the unperforated portions of the inner wheel, and may also be received by such idle holes in both wheels as register.

12. In a perforating-machine, the combination with a group of punches of two independently - adjustable pattern members mounted one behind the other and coöperatively controlling all of said punches.

13. In a perforating-machine, the combination with a group of punches of two independently-adjustable pattern-wheels mounted one within the other and coöperatively controlling all of said punches.

14. In a perforating-machine, the combination with a group of punches of two independently-adjustable pattern members each having perforations and mounted one behind the other; said perforations at each of said 65 members being arranged in a series of groups to form different patterns, and means for enabling any group upon either member to co-

operate with any group upon the other member to control said punches.

15. In a perforating-machine, the combination with a group of punches of two independently-adjustable pattern-wheels, each having perforations and mounted one within the other; said perforations in each of said members being arranged in a series of groups; 75 and means for holding any group upon either wheel in register with any group upon the other wheel, whereby one or more of punches in the group may be controlled by the unperforated portion thereof.

16. In a perforating-machine, the combination with a group of punches, of independently-adjustable combinable pattern devices each having means for controlling said punches.

17. In a perforating-machine, the combination with a group of punches, of two independently-adjustable wheels each having patterns formed by perforations therein, and the patterns of one wheel being combinable with 90 the patterns of the other wheel for controlling all of said punches.

18. In a perforating-machine, the combination with a group of punches, of an arbor or support, and telescopically-connected pattern-wheels mounted upon said support; each wheel being perforated to form a set of patterns, and the patterns upon one wheel being combinable with the patterns upon the other wheel.

19. In a perforating-machine, the combination with a group of punches, of a support, a wheel mounted thereon and having a peripheral flange, holes in said wheel forming a group of patterns for controlling said punches, and a wheel mounted telescopically upon said flanged wheel and also having patterns each formed of groups of holes; the patterns in one wheel being combinable with those in the other.

20. In a perforating-machine, the combination with a group of punches, of a support, a wheel mounted thereon and having a peripheral flange, holes in said wheel forming a group of patterns for controlling said punches, 115 a wheel mounted telescopically upon said flanged wheel and also having patterns each formed of groups of holes, the patterns in one wheel being combinable with those in the other, said outer wheel having an interior flange, and each of said flanges being perforated, and means, including members adapted to be received by said flange perforations, for setting said wheels so that their patterns may coöperatively control the punches.

21. In a perforating-machine, the combination with a group of punches of two pattern-wheels mounted one within the other; said wheels having registrable idle holes for the punches; said idle holes being mounted upon each wheel in a series of groups, and different holes being omitted from the different groups, whereby the punches may be operable by the unperforated portions of the outer

wheel, and may upon passing through the holes in the outer wheel be operated by the unperforated portions of the inner wheel, and may also be received by such idle holes in both 5 wheels as register; a third independently-adjustable pattern-wheel mounted at the side of said wheels; and a group of punches controllable by said third wheel.

22. In a perforating-machine, the combination with a group of punches of two independently-adjustable pattern members mounted one behind the other and coöperatively controlling all of said punches; a second group of punches, and a third adjustable pattern 15 member for controlling said second group.

23. In a perforating-machine, the combination with a group of punches of two independently-adjustable pattern-wheels mounted one within the other and coöperatively controlling 20 all of said punches; a third adjustable pattern-wheel; and a group of punches controllable by said third wheel.

24. In a perforating-machine, the combination with a group of punches of two independently-adjustable pattern members each having 25 perforations and mounted one behind the other; said perforations at each of said members being arranged in a series of groups to form different patterns; means for enabling 30 any group upon either member to coöperate with any group upon the other member to control said punches; a second group of punches at the side of the first group; and a third independently-adjustable pattern member for 35 controlling said second group of punches.

25. In a perforating-machine, the combination with a group of punches of two independently-adjustable pattern-wheels each having perforations and mounted one within the 40 other; said perforations in each of said members being arranged in a series of groups; means for holding any group upon either wheel in register with any group upon the other wheel; whereby one or more of punches 45 in the group may be controlled by the unperforated portion thereof; a third independently-adjustable pattern-wheel mounted by the side of said two wheels; and a second group of punches controlled by said second 50 wheel.

26. In a perforating-machine, the combination with a group of punches, of independently-adjustable combinable pattern devices each having means for controlling said 55 punches; a support for said pattern devices; additional groups of punches, and additional independently-adjustable pattern devices also mounted upon said support.

27. In a perforating-machine, the combination with a group of punches of two independently-adjustable wheels each having patterns formed by perforations therein; the patterns of one wheel being combinable with the patterns of the other wheel for controlling all of 65 said punches; an arbor upon which said wheels are mounted; additional groups of

punches; and additional pattern-wheels also mounted upon said arbor.

28. In a perforating-machine, the combination with a group of punches, of a support; telescopically-connected pattern-wheels mounted upon said support; each wheel being perforated to form a set of patterns, and the patterns upon one wheel being combinable with the patterns upon the other wheel; a second 75 group of punches, and a third pattern-wheel mounted upon said support and controlling said second group of punches.

29. In a perforating-machine, the combination with a group of punches, of a support, a 80 wheel mounted thereon and having a peripheral flange, holes in said wheel forming a group of patterns for controlling said punches, a wheel mounted telescopically upon said flanged wheel and also having patterns each 85 formed of groups of holes, the patterns in one wheel being combinable with those in the other; a third pattern-wheel mounted upon said support and flush with said flange, and a second group of punches controlled by said 90 third wheel.

30. In a perforating-machine, the combination with a group of punches, of a support; a wheel mounted thereon and having a peripheral flange; holes in said wheel forming a 95 group of patterns for controlling said punches; a wheel mounted telescopically upon said flanged wheel and also having patterns each formed of groups of holes, the patterns in one wheel being combinable with those in the 100 other, said outer wheel having an interior flange, and each of said flanges being perforated; means including members adapted to be received by said flange perforations, for setting said wheels so that their patterns may 105 coöperatively control the punches; two additional pattern-wheels set upon said support one at each side of said telescoping wheels; and groups of punches controllable by said additional wheels. 110

31. A perforating-machine comprising a group of punches, two independently-adjustable cryptographic numerical pattern members, and means for punching a universal base-hole; each pattern upon each of said members 115 having means for punching an individual indicative hole, and said punches being located respectively at different points relative to the base-punch, and at three substantially equidistant points in three substantially equidistant rows. 120

32. A date-marker comprising means for making two different base-marks, means for making cryptographic marks at different points upon the left-hand side of the first of 125 the base-marks for indicating the ordinals of the months, means, including a single group of markers, for making cryptographic marks at different points upon the right-hand side of the first base-mark to indicate the days of 130 the month, and means for making cryptographic marks at different points upon the

right-hand side of the second base-mark for indicating the unit digits in the years.

33. A date-perforator comprising means for making two different base-holes, adjustable means for punching cryptographic holes at different points upon the left-hand side of the first of the base-holes for indicating ordinals of the months, adjustable means, including a single group of punches, for punching cryptographic holes at different points upon the right-hand side of the first base-hole to indicate the days of the month, and adjustable means for punching cryptographic holes at different points upon the right-hand side of the second base-hole for indicating the years.

34. A date-perforator comprising means for making two different base-holes, means, including a single group of punches and combinable pattern members for punching cryptographic holes at different points between said base-holes to indicate by their combinations days of the month, and means for punching cryptographic holes in the outer sides of said base-holes to indicate the month and year.

35. A perforating-machine provided with means for punching a universal base-hole, adjustable wheels one within the other, and a single group of punches operable by said wheels in combination for punching individual indicative holes, the indicative punches being respectively located so as to operate at different points with relation to the base-punch, so that by noting the position of the punched indicative holes relative to the universal base-hole, the reader is informed of the characters intended to be represented by the combination of holes.

36. A perforating-machine comprising a device for punching a base-hole, a series of independently-movable punches mounted in a symmetrical group, and adjustable means for operating any selected punch or punches; said adjustable means including a plurality of wheels each having a series of patterns, and each capable of controlling all the punches in the group.

37. A perforating-machine comprising a device for punching a base-hole, a series of independently-movable punches mounted in a symmetrical group, and adjustable means for operating any selected punch in connection with any other selected punch, said adjustable means including wheels each having a series of patterns, and a series of normal characters for guiding the operator in setting the wheel.

38. A perforating-machine comprising a device for punching a base-hole, a series of independently-movable punches mounted in a symmetrical group, and adjustable means for operating any selected punch or punches, said adjustable means including a plurality of wheels having a series of patterns of idle holes, the punches falling opposite the unperforated portions of the patterns being operable by contact with the periphery of either

wheel, a series of normal characters marked upon each wheel to denote the characters corresponding to the various patterns, and means for independently positioning each of said wheels, said normal characters being so placed upon the wheels that when any one thereof is in apposition to said positioning means, the pattern denoted thereby is in operative relation to said group of punches.

39. A perforating-machine comprising a device for punching a base-hole, a symmetrical group of independently-movable punches, and a plurality of adjustable means for operating together any selected punch in the groups; said adjustable means including a plurality of independently-adjustable punch-controlling wheels each having a series of patterns of idle holes, each pattern corresponding to the grouping of the associated punches, except that from each pattern one or more idle holes are omitted, a different hole being omitted from each pattern, so that the punch falling opposite the omitted hole may be driven by contact with the periphery of the wheel.

40. A perforating-machine comprising means for punching two base-holes, a plurality of symmetrical groups of independently-movable punches, and a plurality of adjustable means for operating together any selected punch in the several groups, said adjustable means including a plurality of independently-adjustable punch-controlling wheels each having a series of patterns of idle holes, each pattern corresponding to the grouping of the associated punches, except that from each pattern one or more idle holes are omitted, a different hole being omitted from each pattern, so that the punch falling opposite the omitted hole may be driven by contact with the periphery of the wheel, one wheel with its punches being mounted at one side of one of said base-punches, and a pair of telescopic wheels with one group of punches being mounted between said base-punches, and a fourth wheel with a third group of punches being mounted at the outer side of the second base-punch.

41. A perforating-machine comprising a device for punching a base-hole, a plurality of symmetrical groups of independently-movable punches, and a plurality of adjustable means for operating together any selected punch in the several groups, said adjustable means including a plurality of independently-adjustable telescopic punch-controlling wheels each having a series of patterns of idle holes, each pattern corresponding to the grouping of one group of punches, except that from each pattern one or more idle holes are omitted, a different hole being omitted from each group, so that the punch falling opposite the omitted hole in either wheel may be driven by contact with the periphery of the wheel, and a series of normal characters marked upon each of said wheels, to denote the characters cryptographically indicated

by the holes punched by means of the various groupings.

42. A marking-machine having means for making a universal base-mark, and means including two independently-adjustable telescopic wheels, for making a single series of individual indicative marks, the indicative markers of the wheels being respectively located at different points with relation to the base-marker, and being so interrelated that if collated they would fall in two symmetrical groups, one group at each side of the base-marker.

43. A perforating-machine comprising a universal base-punch and a group of punches of two independently-adjustable wheels, each having upon its periphery a set of cryptographic numerical perforator-patterns, each pattern in each of said sets having means for punching an individual indicative hole, and the indicative perforators of the different patterns so interrelated that if collated they would fall at three substantially equidistant points in three substantially equidistant rows upon the same side of the base-punch.

44. A date-perforator comprising means for making two different base-holes, a wheel having means for punching cryptographic holes at different points upon the left-hand side of

the first of the base-holes, for indicating ordinals of the months, telescopic independently-adjustable wheels having means for punching cryptographic holes at different points between the base-holes, to indicate days of the month, and means for punching cryptographic holes upon the right-hand side of the second base-hole for indicating unit digits of the years.

45. A date-perforator comprising means for making two different base-holes, an adjustable wheel having means for punching cryptographic holes at different points upon the left-hand side of the first of the base-holes, for indicating ordinals of the months, telescopic independently-adjustable wheels having means for punching cryptographic holes at different points between said base-holes to indicate days of the month, and an adjustable wheel having means for punching cryptographic holes at different points upon the right-hand side of the second base-hole, for indicating unit digits of the years.

Signed at Nos. 9 to 15 Murray street, New York, N. Y., this 21st day of April, 1903.

ALFRED L. DAY.
